UNITED STATES PATENT OFFICE.

EUGEN GEIGER, OF KARLSRUHE, GERMANY.

ROTATING ENDLESS SCREEN BELT FOR THE MECHANICAL PURIFICATION OF WATER.

Application filed March 5, 1926, Serial No. 92,630, and in Germany March 7, 1925.

My invention relates to rotating endless screen belts for the mechanical purification of water, built up of a number of screen sections tightly held in suitable frames that are carried on both sides by an endless chain. It is known to remove from the belt the impurities deposited thereon by spraying off the same with water under pressure issuing in fine jets from a pipe provided horizontally behind the upper end of the front part of the belt and flowing forwardly through the screens. The spraying water meets not only with the free screen surface of the rotating belt but also with the cross members of the screen frames which do not allow the water to pass through but stray or scatter it unnecessarily. The strayed water meets also with the screen sections that have not yet been lifted over the trough arranged in front of the upper end of the front part of the belt and serving to catch, collect and carry away the impurities sprayed off from the same, thus prematurely rinsing away the impurities deposited on these sections. This involves not only an undue loss of spraying water but also a disturbance of the purifying operation. To avoid this disadvantageous effect, I provide means for automatically throttling the spraying water during the passage of the cross members of the screen frames in front of the spraying pipe.

The accompanying drawings illustrate a form of construction of the apparatus embodying my invention, Fig. 1 showing the upper end of the screen belt with a part of one of the two upper chain wheels, the spraying device and the collecting trough in side elevation, partly in vertical section, Fig. 2 showing one of the upper chain wheels with the spraying device in front elevation, and Fig. 3 showing parts of one of the upper chain wheels and of the spraying device on a larger scale in side elevation, partly in section.

For spraying off from the screen belt *a* the impurities deposited thereon there are provided two pipes *b* and *c* for water under pressure, one of which, *b*, lies immediately and horizontally behind the upper end of the front part of the belt and sends fine jets of water issuing through small holes provided in two series in its front horizontally and outwardly through the screen passing in front of it, whilst the second pipe *c* lies immediately and horizontally in front

of the said belt end and at a certain distance above the first pipe and sends fine jets of water issuing through a series of holes provided in its bottom downwardly along the belt.

Into the supply pipe *d* leading to the inner pipe *b* there is inserted a balanced valve *e* which is held in the open position by spring pressure. The casing of this valve supports a bracket in which a double armed lever *f* is fulcrumed. One end of this lever is jointed to the spindle *g* of the valve *e*, whilst the other end carries a roller *h*. This roller runs upon the periphery of one of the two upper chain wheels *i* guiding the belt *a*. The periphery of this chain wheel is provided with a number of cams *k*, the distance of which corresponds to that of the cross members *l* of the screen frames, and the length of which in the direction of the periphery corresponds to the width of these frame members. The said cams are disposed in such manner that always immediately before the arrival of the lower cross member *l* of one screen section below the spraying pipe *b* one of the cams runs upon the roller *h*, thus raising the body of the valve *e* into the closed position by means of the lever *f* and the spindle *g*, and that immediately after the passage of the upper cross member *l* of the following screen section in front of the pipe *b* the said cam runs off again from the roller *h*, thus allowing the valve *e* to open again under the spring pressure. In this manner always during the passage of two neighboring frame members *l* in front of the series of holes in the pipe *b* the supply of water to this pipe is automatically stopped and thus the spraying action of this pipe on the belt *a* is interrupted, whereby straying or scattering of spraying water is prevented and saving of water under pressure is obtained. The jets of spraying water issuing from the outer pipe *c* and continually spraying the belt from above cleanse also that parts of the screen sections which are not struck by the jets issuing from the inner pipe *b*.

What I claim as my invention and desire to secure by Letters Patent is:

1. In a rotating endless screen belt for the mechanical purification of water, having a front and a rear part and being built up of a number of screen sections, in combination with a number of frames holding said screen sections and having cross members, a

2

spraying pipe provided behind the upper end of the front part of the belt, means for supplying water under pressure to said spraying pipe, and means for automatically 5 throttling the water supply during the passage of said cross members of said frames in front of said spraying pipe.

2. In a rotating endless screen belt for the mechanical purification of water, having a front and a rear part and being built 10 up of a number of screen sections, in combination with a number of frames holding said screen sections and having cross members, two endless chains carrying said frames 15 on both sides and running over chain wheels, the periphery of one of said chain wheels being provided with a number of

cams the distance of which corresponds to that of said cross members and the length of which corresponds to the width of said cross members, a spraying pipe provided behind the upper end of the front part of the belt, a supply pipe for water under pressure leading to said spraying pipe, a valve inserted into said supply pipe and held in the open position by spring pressure, means provided on said valve and adapted to be operated by said cams so as to close said valve during the passage of said cross members in front of said spraying pipe. 20 25 30

In testimony whereof I affix my signature.

DR. EUGEN GEIGER.
